UNITED STATES PATENT OFFICE

OSWALD ULRICH, OF CHICAGO, ILLINOIS, ASSIGNOR TO EMIL J. PAIDAR CO., OF CHICAGO, ILLINOIS, A CORPORATION OF ILLINOIS

PAPER HOLDER AND CUTTER

Application filed November 25, 1927. Serial No. 235,432.

This invention relates to improvements in paper holders and cutters, and more particularly to paper holders and cutters of the type commonly found on barber chairs, or service chairs of a similar nature. The present invention contemplates the provision of a paper holder and cutter adapted to be used in conjunction with the paper passing over the headrest of a service chair, but which, of course, may be used for many other varied purposes as will become apparent to one skilled in the art.

In the past, devices of this nature have proven more or less objectionable in that they did not permit of sufficiently free movement of the paper. In most instances in such previously known devices, undue difficulty was experienced by operators in releasing the clamping action of the holder, and even when the device was in released position, the passage for the paper was so tortuous that the paper frequently tore within the device, thereby necessitating obviously irksome and costly delays.

The present invention is designed to overcome the above noted defects and objections in the provision of a paper holder and cutter which, when in released position, provides a relatively wide and extremely smooth runway for the paper. The invention also seeks to provide a device of the character described herein, which is easily and readily manipulated, being provided with means permitting positive manual operation of the same with substantially no danger of the clamping element slipping from the fingers of the operator and accidentally snapping into holding position while the paper is being run.

A further object of this invention is to provide a device of this character wherein the paper may be easily cut, and the trim margin remaining in the device may be readily and easily grasped by the hand of the user.

While some of the more salient features and characteristics of a device embodying this invention have been above pointed out, others will become apparent from the following disclosures.

The invention includes these and other features of construction and combinations of

parts hereinafter described and shown in a preferred form in the drawings, as more particularly indicated by the claims.

In the drawings:

Figure 1 is a fragmentary side elevational view of a service chair equipped with the device embodying principles of the present invention.

Figure 2 is a fragmentary elevational view of a portion of the service chair with the device mounted thereon.

Figure 3 is a rear elevational view of the device itself, taken substantially along line III—III of Figure 2.

Figure 4 is a longitudinal sectional view of the device taken substantially along line IV—IV of Figure 2.

Figure 5 is a transverse sectional view taken along line V—V of Figure 4.

As shown in the drawings:

In the illustrated embodiment of the present invention there is shown a service chair 1 provided with the usual headrest 2 on which is mounted a container 3 adapted to rotatably hold a roll of paper or the like. The paper, of course, passes in a continuous sheet 4 over the headrest and is engaged at the rear thereof by a holder and cutter 5 in which the novel features of the present invention are centered.

The holder and cutter 5 comprises a housing 6 preferably formed from a single stamping, and is provided with apertured securing lugs 7 which are angularly disposed relative to the housing and by which the device is mounted to a headrest or the like. Preferably integral with the housing is a top wall 8 which extends forwardly beyond the housing proper and provides a runway for the paper 4 on its under surface, the paper sheet 4 entering the housing through a slot 9 in the back thereof, which slot is disposed just below the wall 8. The wall 8 is provided at its outer edge with an arcuate or angularly disposed lip 10 for a purpose that will later appear.

Pivottally or rotatably mounted within the housing, in any desired manner, or, as shown, by the stud screws 11, is an angular member 12 provided with a substantially flat upper

side 13, the inner edge of which is preferably serrated as indicated at 14. The stud screws 11 pivotally engage an ear 15 disposed at each end of the member 12. As seen more clearly in Figure 5 these ears are relatively extended nearly the width of the housing. Disposed beneath the flat portion 13 at each end thereof is a coiled spring 16 which abuts the flat portion 13 adjacent its inner edge and the bottom of the housing 6, to thereby force the serrated edge 14 into substantial abutment with the under side of the top wall 8. Adjacent each of the springs 16, a lug 17 is struck from the housing 6 and bent to a substantially vertical position to aid in retaining the springs in their proper position. To facilitate manual operation of the device, a lever 18 is provided preferably integral with the pivotal member 12.

As seen more clearly in Figure 5, when the serrated edge 14 on the pivotal member 12 is normally pushed upwardly by the springs 16, it will clamp the paper sheet 4 against the wall 8 and prevent movement of the paper. As indicated by the dotted lines, when the clamping member 12 is manually actuated by means of the lever 18, the flat portion 13 will pivot downwardly away from the top wall 8, which pivotal motion is limited by the contact of the rear portion of the ears 15 with the bottom of the housing 6. The flat portion 13 will, therefore, assume a position just below the longitudinal slot 9 and be substantially parallel with the top wall 8, to complete a smooth and free runway for the paper 4. It will be apparent, therefore, that when a user of the device desires a new portion of the sheet, he merely squeezes the lip 10 on the top wall 8 and the lever 18 between the thumb and finger, draws the sheet through to the desired length and releases the lever 18 to permit the clamping member to again engage the paper. To cut the paper to any desired size it is merely necessary to pull the strip 4 against the edge of the lip 10. If so desired, the edge of this lip may be sharpened or serrated, but it has been found that the relatively sharp edge remaining when the original stamping is made, is entirely sufficient for this purpose.

It is to be especially noted that the lip 10 provides positive and practical non-slipable gripping means for the hand of a user, when actuating the clamping member through the lever 18. This lip also provides means for quickly engaging the remaining margin of paper left under the top wall 8 after a portion has been cut off. It is also to be especially noted that when the clamping member is in its released position, the paper is free to run through the entire area of the slot 9 with no obstructions whatever to its passage.

From the foregoing it is apparent that I have provided a novel paper holder and cutter, especially desirable for use with service

chairs, and which provides substantially perfect freedom of motion for the paper, means for positively actuating the device with no danger of the clamping member slipping from the grasp of a user until released, and means for readily gripping the paper. Moreover, the present invention may be formed from sheet metal by simply stamping and bending operations, is pleasing in appearance, easily mounted for use, and very economical to manufacture.

I claim as my invention:

1. In a device of the character described, a housing having an open front, the rear wall of said housing having a slot therein adjacent the top wall of said housing, said top wall projecting forwardly and forming a smooth runway for a strip of paper entering said housing through said slot, a pivotal member in said housing normally pressing said paper against said top wall to block said runway, means projecting out of said housing to actuate said pivotal member to release said paper, and means for limiting the movement of said pivotal member to a position substantially parallel to said top wall and adjacent the lower edge of said slot.

2. In a device of the character described, a housing open at one side thereof, the opposite side wall of said housing having a slot therein adjacent a second wall of said housing for admitting a strip of paper, a pivotal member in said housing normally blocking the passage of said paper, and means for actuating said member into a position substantially parallel to said second wall and adjacent the opposite edge of said slot to thereby form a smooth runway for said paper.

In testimony whereof I have hereunto subscribed my name at Chicago, Cook County, Illinois.

OSWALD ULRICH.
